CLAIM

The ornamental design for a card case for phone, as shown and described.

DESCRIPTION

FIG. 1 is a perspective view of a card case for phone showing my new design in a first position;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front view of the card case for phone of FIG. 1 shown in a second position;

FIG. 9 is a back view thereof;

FIG. 10 is a perspective view of the card case for phone of FIG. 1 shown in a third position;

FIG. 11 is a perspective view of the card case for phone of FIG. 1 shown in a fourth position;

FIG. 12 is a perspective view of the card case for phone of FIG. 1 shown in a first position in an environment of use;

FIG. 13 is another perspective view thereof;

FIG. 14 is another perspective view thereof;

FIG. 15 is a perspective view of the card case for phone of FIG. 1 shown in a fifth position in an environment of use; and,

FIG. 16 is a perspective view of the card case for phone of FIG. 1 shown in a second position in an environment of use. Broken lines illustrate portions of the card case for phone that form no part of the claimed design. Additional broken lines in FIGS. 12-16 illustrate environment and form no part of the claimed design.

1 Claim, 16 Drawing Sheets
